UNITED STATES PATENT OFFICE.

LUTHER L. KNOX, OF AVALON, PENNSYLVANIA, ASSIGNOR TO KNOX PRESSED & WELDED STEEL COMPANY, OF PITTSBURGH, PENNSYLVANIA, A CORPORATION OF PENNSYLVANIA.

METHOD OF MAKING ANNEALING-BOXES.

1,187,067.

Specification of Letters Patent. Patented June 13, 1916.

Original application filed April 17, 1915, Serial No. 22,079. Divided and this application filed March 4, 1916. Serial No. 82,193.

To all whom it may concern:

Be it known that I, LUTHER L. KNOX, a citizen of the United States, residing at Avalon, in the county of Allegheny and 5 State of Pennsylvania, have invented a new and useful Method of Making Annealing-Boxes, of which the following is a full, clear, and exact description, reference being had to the accompanying drawings, forming part 10 of this specification, in which—

Figure 1 is a top plan view, partly broken away, of an annealing box constructed in accordance with my invention. Fig. 2 is a front elevation. Fig. 3 is a transverse section. Fig. 4 is a plan view showing the preferred form of blank which may be employed in making the box, the successive steps of the forming operation being indicated by dotted lines, and Fig. 5 is a section view of the blank, and also indicating in dotted lines the successive forming steps.

My invention has relation to annealing boxes, and is designed to provide a novel method of forming such boxes, whereby they 25 may be shaped in one integral piece without joints or seams, from a sheet metal blank. Also to provide a method of this character in which provision is made in a novel manner for expansion and contraction movements, and for taking care, in a beneficial way, of excess metal resulting from the forming operations.

The present invention is a division of my pending application Serial No. 22,079, 35 filed April 17, 1915.

In the accompanying drawings, in which I have shown the preferred form of box embodying my invention, the numeral 2 designates the body of the box which is open 40 at the bottom, and 3 the integral arched top. The box is, in general, of the usual oblong form, but is provided at each of its corner portions with an outward swell or bend 4, extending beyond the general planes of the 45 sides and ends of the box.

5 designates lifting lugs which are secured preferably by welding to opposite sides of the box.

The box is made from a single integral 50 sheet of metal by successive drawing operations. I preferably start with a blank 6 of the general form shown in Fig. 4. In the first drawing or shaping step, the box is

given the general oval shallow form indicated at 7 in dotted lines in Figs. 4 and 5. 55 In the next forming step, it is given the deeper and generally oblong rectangular form shown at 8, in said figures. In the next step, the sides and ends of the box are compressed, and the outwardly bulged 60 corner portions 4 are formed.

It will be noted by reference to Fig. 4 that those portions of the blank which are to form the corner portions of the finished box are cut away, as indicated at 9 in Fig. 4, so 65 as to prevent excess of metal at the corners. The upward bulges or swells at the corners provide more or less flexible portions which will take up the expansion and contraction of the box in use, and prevent its giving way as 70 a result of strains due to expansion and contraction. The bulges also permit the box to be more readily placed in position over a pile of plates or sheets. The bulged corner portions also provide for taking up the excess of metal at the corners, as otherwise in forming a box with corners from a single 75 plate or sheet, the metal would necessarily be lapped or folded at the corners.

My invention provides a one-piece box 80 which is entirely free from joints and seams and which is much lighter and less likely to become broken or cracked in service than the usual cast box. There are no rivets or other weak points to give way in service, and 85 all sharp corners or angles are avoided.

I claim:

1. The herein-described method of making annealing boxes, which consists in providing an integral sheet metal blank, shaping 90 said blank to give it an oval shallow box form, then reducing the transverse dimensions of such form to give a generally rectangular form to the box, and at the same time gradually deepening the box, and in 95 said operations permitting the excess metal to form outward swells or bulges at the vertical corners of the box, substantially as described.

2. The herein-described method of making 100 annealing boxes, which consists in providing a sheet metal blank of generally rectangular form with its corner portions cut away, subjecting said blank to a series of die forming and drawing operations, whereby the blank 105 is first given a generally oval shallow box

form, its side and end walls are then contracted to give a generally rectangular form, and the depth of the box gradually increased, and in said operations permitting the excess metal to form outward swells or bulges at the vertical corners of the box, substantially as described.

3. The herein described method of making jointless and seamless annealing boxes, which
10 consists in providing an integral sheet metal blank having the corner portions thereof cut away, shaping said blank to give it an initial oval shallow boxlike form, then reducing the transverse dimensions of said
15 form to give a generally rectangular shape

to the box and at the same time gradually deepening the box, and in said operations permitting the excess metal resulting from the reduction of the transverse dimensions to form outward swells or bulges at the vertical corners of the box, and retaining such swells or bulges in the finished article, substantially as described. 20

In testimony whereof, I have hereunto set my hand.

LUTHER L. KNOX.
